SET OF PLAYING CARDS

Rachael C. Davis, Lockridge, Iowa

Application January 25, 1949, Serial No. 473

Term of patent 14 years

(Cl. D34—13)

To all whom it may concern:

Be it known that I, Rachael C. Davis, a citizen of the United States, and a resident of Lockridge, in the county of Jefferson and State of Iowa, have invented a new, original, and ornamental Design for a Set of Playing Cards, of which the following is a specification, reference being had to the accompanying drawing, forming a part thereof.

Figures 1 to 17 are face views of the cards in the set of playing cards showing my new design.

In the set of 53 cards there is one card as illustrated in Fig. 1; one of Fig. 2; one of Fig. 3; one of Fig. 4; one of Fig. 5; one of Fig. 6; one of Fig. 7; one of Fig. 8; one of Fig. 9; one of Fig. 10; ten of Fig. 11; one of Fig. 12; one of Fig. 13, ten of Fig. 14; ten of Fig. 15; one of Fig. 16 and ten of Fig. 17.

The backs of the cards, being the reverse of those shown, may be blank or printed in a conventional card back design.

I claim:

The ornamental design for a set of playing cards, as shown and described.

RACHAEL C. DAVIS.
